by Lewis A. Maxon

Atty.

UNITED STATES PATENT OFFICE

LEWIS J. CLAPP, OF CLAREMONT, NEW HAMPSHIRE, ASSIGNOR TO SULLIVAN MACHINERY COMPANY, A CORPORATION OF MASSACHUSETTS

PORTABLE COMPRESSOR MECHANISM

Application filed November 20, 1929. Serial No. 408,626.

My invention relates to an improved portable compressor mechanism, and more particularly to an improved accessory which is used in connection with the driving means for the compressor.

One object of my invention is to provide improved portable compressor mechanism. A further object of my invention is to provide improved means for warming up the water or other cooling medium used in connection with the driving means for compressor mechanism. A further and more specific object of my invention is to provide heat exchange means which may be used in connection with the starting unit for a driving engine for heating up a fluid which is normally used in cooling said driving means. Further objects of my invention will become apparent in the course of the ensuing description, and 20 pointed out in the accompanying claims.

For the purpose of illustrating my invention I have shown in the accompanying drawings an illustrative embodiment of my invention; and in these drawings,

25 Fig. 1 is a view in side elevation of a portable compressor mechanism in which a compressor is driven by a Diesel engine, and in which the cooling fluid for the Diesel engine may be heated up by a coil connected with the starting unit for the Diesel engine.

Fig. 2 is a detailed view, partially in side elevation and partially in section, showing the connections between the heating coil and adjacent portions of the conduits for circulating the cooling medium for the compressor mechanism.

In this illustrative embodiment of my invention there is disclosed a frame 5 mounted on wheels 6, and supporting a Diesel engine 16 and a compressor mechanism 9 driven thereby. A receiver tank 7 and a fuel tank 8 are carried at the rear end of the frame 5. The compressor mechanism 9 is connected to the receiver tank 7, so as to deliver compressed fluid thereto through piping 10. The compressor mechanism 9 is provided with cooling jackets to which cooling fluid is delivered through a pipe 11, and from which this fluid is led away through a pipe 12. A 45 radiator 13 is supported at the front end

of the frame 5; and a horizontal pipe 14 runs longitudinally of the portable compressor so as to conduct the cooling fluid from the compressor mechanism 9 to the jackets of the Diesel engine, whence it is delivered to the radiator 13. A pump 15 forces the fluid from the pipe 14 into the jackets of the compressor and the Diesel engine, the pump being driven whenever the Diesel engine 16 is running.

The Diesel engine 16 is customarily started by means of a small gasoline engine 17, which is not provided with cooling jackets; and, therefore, delivers its exhaust gases at a high temperature. Instead of exhausting these hot gases directly to the atmosphere, a coil 18 is connected to the exhaust of the unit 17 by a pipe 19. A vent 20, which opens to the atmosphere, is connected to the end of the coil 18. The coil 18 is enclosed within a casing 21, so that cooling fluid may surround the same. The piping 11 includes a T 22, so as to provide a connection for branch piping 23 connected to a threaded opening in the lower portion of the casing 21. A globe valve 24 is provided for controlling the flow 75 of fluid through the branch connection 23. A pipe 25 is threaded into the top of the casing 21, so as to connect the same with the longitudinally extending pipe 14. A globe valve 26 is provided in the piping 11, so as 80 to control flow of fluid into the cooling jackets of the compressor mechanism 9. Clutch mechanism (not shown) is provided in the driving connections 27 between the Diesel engine and the compressor mechanism. 85

The operation of this embodiment of my invention is as follows: When the Diesel engine is to be started, the clutch mechanism is operated to disconnect the compressor mechanism 9 from the Diesel engine 16. The 90 starting unit 17 is then set in motion, the exhaust gases passing through the pipe 19 and heating coil 18 to the atmosphere by way of vent 20. The valve 26 is closed and the valve 24 is opened. The hot exhaust gases 95 from the starting unit 17 heat the fluid surrounding the coil 18; and a circulation of fluid is initiated, the same passing through T 22 and piping 23 into the casing 21, and from the casing 21 through pipes 25 100 and from the casing 21 through pipes 25

and 14, to the Diesel engine, so as to cause warm fluid to flow into the jackets of the Diesel engine. When enough warm fluid has passed into these jackets, the starting unit 5 17 is connected in the customary manner to the Diesel engine 16, and the latter is started. The globe valve 26 is then opened for normal circulation of fluid through the cooling jackets of the compressor mechanism 9. The 10 globe valve 24 may then be turned so as to throttle down or completely close off the circulation of fluid through the branch piping 23.

It has often been extremely difficult in cold 15 weather to start a Diesel engine, even though a gasoline engine, such as the starting unit 17, be employed. The lubricating grease or oil may become so congealed as to make it 20 hardly possible to even turn the Diesel engine. It greatly facilitates starting of the Diesel engine to have its jackets filled with warm fluid. The starting unit 17 provides a very convenient stove for quickly heating up fluid which may then be circulated into 25 the jackets of the Diesel engine. By my improved combination of parts I have provided an arrangement for expeditiously starting a Diesel engine, even in cold weather. This arrangement does not interfere with the 30 normal operation of the compressor mechanism; and is a compact arrangement so as not to require extra space in the portable outfit disclosed herein.

While I have in this application specifically 35 described one form which my invention may assume in practice, it will be understood that this form of the same is shown for purposes of illustration and that the invention may be modified and embodied in various 40 other forms without departing from its spirit or the scope of the appended claims.

What I claim as new and desire to secure 45 by Letters Patent is:

1. In combination, a jacketed engine, an 45 internal combustion engine for starting said jacketed engine, means for conducting cooling fluid to and from the jackets of said jacketed engine, and a heat exchange device connected in said cooling fluid conducting means and connected to receive exhaust gases from said internal combustion engine.

2. In combination, a jacketed engine, a 55 radiator, means for conducting cooling fluid in a closed circuit through said radiator and the jackets of said engine, an internal combustion engine accessory to said jacketed engine, and a heat exchange device connected in said cooling fluid conducting means for circulating warmed fluid to the jackets of 60 said jacketed engine, and connected to receive exhaust gases from said internal combustion engine.

3. In combination, a jacketed engine, a 65 jacketed pumping mechanism adapted to be driven thereby, means for conducting cool-

ing fluid in a closed circuit through the jackets of said pumping mechanism and through the jackets of said engine, fluid conducting means for bypassing the jackets of said pumping mechanism, an internal combustion engine for starting said jacketed engine, and a heat exchange device connected in said bypass fluid conducting means and connected to receive exhaust gases from said internal combustion engine.

4. In combination, a jacketed engine, a jacketed pumping mechanism adapted to be driven thereby, a radiator, means for conducting cooling fluid in a closed circuit through said radiator and through the jackets of said pumping mechanism and the jackets of said engine, an internal combustion engine for starting said jacketed engine, and a heat exchange device connected to receive cooling fluid from said conducting means and return the same in warmer condition to said conducting means, said heat exchange device being connected to receive exhaust gases from said internal combustion engine.

5. In combination, a jacketed engine, a jacketed compressor mechanism adapted to be driven thereby, a radiator, means for conducting cooling fluid in a closed circuit through said radiator and through the jackets of said compressor mechanism and the jackets of said engine, fluid conducting means for bypassing the jackets of said compressor mechanism, an internal combustion engine for starting said jacketed engine, and a heat exchange device connected in said bypass fluid conducting means and connected to receive exhaust gases from said internal combustion engine.

6. In combination, a jacketed engine, a jacketed pumping mechanism adapted to be driven thereby, means for conducting cooling fluid in a closed circuit through the jackets of said pumping mechanism and through the jackets of said engine, fluid conducting means for bypassing the jackets of said pumping mechanism, a valve for controlling said bypass fluid conducting means, an internal combustion engine for starting said jacketed engine, and a heat exchange device connected in said bypass fluid conducting means and connected to receive exhaust gases from said internal combustion engine.

7. In combination, a jacketed engine, a jacketed compressor mechanism adapted to be driven thereby, a radiator, means for conducting cooling fluid in a closed circuit through said radiator and through the jackets of said compressor mechanism and the jackets of said engine, fluid conducting means for bypassing the jackets of said compressor mechanism, a valve for controlling the flow of fluid through said bypass fluid conducting means, an internal combustion engine for starting said jacketed engine, and a heat ex-

change device connected in said bypass fluid conducting means and connected to receive exhaust gases from said internal combustion engine.

5 8. In combination, a jacketed internal combustion engine, an internal combustion engine for starting said jacketed engine, and means for conducting fluid to and from the jackets of said jacketed engine including means providing parallel paths of flow for conducting cooling fluid between the exit from and the entrance to said jackets, the means providing one of said parallel paths including a heat exchange device connected to receive heat from the starting engine.

10 9. In combination, a jacketed internal combustion engine, an internal combustion engine for starting said jacketed engine, and means for conducting fluid to and from the jackets of said jacketed engine including means providing parallel paths of flow for conducting cooling fluid between the exit from and the entrance to said jackets and means for limiting flow to one or the other 15 of the paths at will, the means providing one of said parallel paths including a heat exchange device connected to receive heat from the starting engine.

In testimony whereof I affix my signature.
